DOOR SUSPENSION, ESPECIALLY FOR
TRUCKS AND TRAILERS

Edmund T. Ridgway, Oaklyn, N. J., assignor to
The Budd Company, Philadelphia, Pa., a corporation of Pennsylvania

Application November 19, 1947, Serial No. 786,892

7 Claims. (Cl. 16—162)

1

The invention refers to a door suspension and especially to a door suspension for a vehicle body. More particularly, the invention refers to the suspension of doors of automobile trailers, trucks and the like.

Among the objects of the invention is a door suspension of the indicated type and a hinge construction for such suspension which afford a firm connection between the door and the supporting wall, which connection is continuous along one margin of the door but is considerably lighter and less expensive than the known continuous door suspensions using the so-called piano hinges.

The aforesaid objects of the invention are achieved mainly by a door suspension having a piano-type hinge between adjoining vertical margins of door frame and door, which hinge extends over the major portion of the length of such margins and is characterized by leaves of relatively light strength or gauge in the middle portion of the length of the hinge and of considerably heavier strength or gauge in the end regions. The strong end portions of the leaves, consequently, are arranged in the regions where the hinge has to sustain by far the greatest stresses, whereas the light middle portions of the leaves maintain the continuity of the hinge, afford a continuous seal along the hinged margins, insure proper alignment of wall and door over their entire height, and retain the ease of installation of piano-type hinges as compared with suspensions employing a number of separate hinges.

The above-outlined and other objects, advantages and features of the invention will be more fully and more easily understood from the embodiment illustrated in the attached drawing and described hereinafter.

In the drawing:

Figure 1 is a diagrammatic small-scale side elevation of the body of a freight trailer;

Figure 2 is a side elevation of the door of the trailer body shown in Figure 1 on a somewhat larger scale;

Figures 3 and 4 are fragmentary sections through the door and the adjoining trailer walls along lines 3—3 and 4—4 of Figures 1 and 2 on a still larger scale;

Figure 5 is a fragmentary end elevation of the hinge side of the door shown in Figure 2 on about the scale of Figures 3 and 4;

Figure 6 is a section through the end portions of the hinge substantially along lines 6—6 of Figure 5; and

Figure 7 is a section through the middle portion of the hinge along line 7—7 of Figure 5.

2

The illustrated trailer body has a side wall 10 surrounding a door opening closed by a door 11. The door opening is defined by a frame having a threshold 12, a header 13, a lock rail 14, and a hinge rail 15. These members, together with the corrugated sheet metal panelling 16, roof supporting rail 17, the roof 18, further vertical posts (not shown), and the floor structure 19, may form a self-supporting unit not requiring a separate chassis frame. The posts 14 and 15 are formed for holding the adjoining margins of inner panels 20 consisting of plywood or the like. The hinge post 15 is composed of a channel section 21 and an angle section 22, which overlap each other by arms extending transversely to the plane of the side wall, thereby affording a double-thickness jamb portion for the attachment of the hinge to be described later on.

Along its top, bottom, and lock margins, the door 11 has Z-section rails 23 which, by their outwardly directed arms 24, form a door overlap and are overlappingly secured, preferably by electric spot welding, to the outer sheet metal covering 25, 26. The covering 25 is corrugated, whereas the small cover portions 26 are smooth for the attachment of the lock mechanism, which is not shown. The hinge rail 27 is of channel section and has its outer wall 28 overlappingly secured to the outer cover 25. The rails 23 and 27 are reinforced by channel sections 29 inserted between and secured to the inner arms or walls 30 of said rails and the outer cover 25, 26. The door may be further reinforced by a vertical Z-section 31 and covered by an inner panel 20'. All or most of the members entering into the body and door construction may consist of high-tensile sheet metal, preferably cold rolled austenitic stainless steel, which are connected with each other by electric spot welding.

The door 11 is swingably supported on post 15 of the side wall by a piano-type hinge 32 extending over practically the entire height of the door and door opening. This hinge has a pintle or pivot pin 33 extending uninterruptedly over the entire length of the hinge and passing through the rolled-in portions of the leaves 34, 35 and 36, 37.

While an ordinary piano hinge has one pair of leaves with uniform cross section over the entire length of the hinge, the illustrated hinge embodying the invention has three pairs of leaves arranged in series on the pintle 33. The leaves 34, 35 of the pairs at the ends of the hinge are of heavier material than the leaves 36, 37 of the middle pair. The strength of the end por-

tions 34, 35 of the leaves is such as to adapt them for sustaining all or at least the major portion of the stresses to be transmitted from the door to the wall when the door is open. The important function of the middle portions 36, 37 of the leaves is to hold door and wall in appropriate alignment so that, for instance, the door and side wall may not buckle in different directions and thereby bring their planes out of alignment with consequent unsightly appearance of the body.

A further function of the middle portions 36, 37 of the hinge is to afford a continuous seal between door and door post along the hinge margin. Also, the new type hinge retains the great advantage of all piano-type hinges, that is, no alignment difficulties have to be taken care of, as is the case with a plurality of separate hinges requiring care of adjustment to insure coaxial arrangement of their pintles.

The pintle is slightly longer than the aggregate length of the leaves. The end leaves 34 and 35 are movable along the pintle 33 and are slightly spaced from the central leaves 36, 37 with the result that the distance between the end leaves may be accurately adjusted during the attachment of the hinge. The ends of the pintle should be riveted over so as to hold the leaves together before their attachment and so as to prevent the pintle from falling out.

The outer or attachment surfaces of the end leaves and of the central leaves are arranged in planes having the same distance from the axis of the pintle so that these surfaces may be brought into the planes of the attachment surfaces of door rail and door post. This coplanar arrangement of the attachment surfaces of the hinge leaves is achieved by the outward offsetting of the central hinge leaves as shown in Figure 7. The leaves 35 and 37 are provided with holes 38 and 39.

The leaves 34 and 36 are secured to the door, before the insertion of the door into the wall, by electric spot welding or other appropriate methods. This connection is preferably made in such a manner that an accurate predetermined distance between holes 38 in the end leaves 34 is obtained. An assembly jig may be employed for this purpose. Inaccuracies of the length of the hinge or its component parts are adjusted by sliding the end leaves on the pintle as explained hereinbefore.

Prior to the securement of the hinge and of the door to the door post 15, the latter is provided in its jamb face with holes corresponding in number and arrangement to the holes 38, 39 in the hinge leaves. The corresponding holes in the end leaves 35 and in the post 15 are punched or drilled accurately to the size of connecting bolts 40 or the like; these holes in the post are tapped, if screw bolts are used.

The holes 39 in the middle leaf 37 may be somewhat oversized and the attachment screws entering into the correspondingly arranged holes in the post 15 may be self-tapping. Inasmuch as the central hinge portion does not sustain substantial stresses a close fit between the connecting means and the holes 39 of the central hinge leaf is not required. On the other hand, the provision of oversized holes greatly facilitates the assembly and automatically takes care of manufacturing inaccuracies.

The new hinge lends itself to the economical manufacture of different length hinges. One standard form and size of end leaves may be used in combination with pintles and middle

leaves cut to lengths corresponding to different desired lengths of hinges. It is also easy to make a shorter hinge of an available hinge by merely shortening the middle leaves and the pintle.

The new suspension is particularly adapted for doors swingable about an upright axis, that is, for door suspensions which have to sustain great stresses which are largely concentrated at the ends of the margins hinged together.

While only one embodiment of the invention is illustrated and shown, it should be understood that the invention is liable to modifications and adaptations. It is obvious, for instance, that the light gauge middle portions and the heavy gauge end portions of the hinge might be formed integrally with each other. With such modifications and adaptations in view, which will easily occur to those skilled in the art, protection is sought for the invention as covered by the spirit and the language of the attached claims.

What is claimed is:

1. In a vehicle body having a body wall surrounding a door opening and a door in said opening, a hinge connecting said door along one of its sides to said wall swingably about an upright axis, extending continuously over the major portion of the height of said door, and having a pintle and hinge leaves substantially coextensive with the pintle's length, said leaves having end portions, near the top and the bottom, respectively, of said door and door opening, of greater thickness than the thickness of the hinge portion interconnecting said end portions.

2. In a vehicle body having a door frame and a door therein, a continuous hinge connecting adjoining upright margins of said frame and door with each other and extending over the greater part of the length of such margins, said hinge having three pairs of hinge leaves arranged seriatim and interconnected by a single pintle, two of said pairs of leaves being of short length, of heavy gauge material and arranged one at each end of the hinge, the third pair of leaves being arranged between the other two pairs, extending over the major portion of the length of hinge and being of lighter gauge material than said two pairs of hinge leaves at the ends.

3. A hinge of the piano hinge type having three pairs of leaves arranged in series on a single pintle, the greater portion of the length of the hinge being formed by the middle pair of leaves made of lighter gauge material than the end pairs of leaves which latter extend over minor portions only of the length of the hinge.

4. A hinge of the piano hinge type having three pairs of leaves arranged in series on a common pintle, the end pairs of leaves being of thicker material than the middle pair of leaves, at least one of the end pairs of leaves being slideable on the pintle so as to allow adjustment along the length of the pintle.

5. An elongated narrow hinge having leaves, each with end portions of heavy gauge material and a middle portion of lighter gauge material, the lighter gauge leaf portion being offset so that the attachment surfaces of these leaf portions are coplanar with the attachment surfaces of the heavy gauge end portions.

6. Method of securing a door in a door frame by means of an elongated hinge of the type having three pairs of leaves arranged in series on a common pintle, the end pairs of leaves being of

thicker material than the middle pair of leaves and at least one of the end pairs of leaves being slidable on the pintle, the method comprising the step of providing holes in an accurate pattern in the one set of said leaves arranged on the one side of the pintle, the step of providing one of said door and said frame with an identical pattern of holes, the step of securing by welding the set of said hinge leaves arranged on the other side of the pintle to the other one of said frame and door while holding the leaves so that the holes in them follow accurately said pattern, and the final step of securing the first-named leaves by means passing through the holes in such leaves and the said holes in one of said door and frame.

7. In a method according to claim 6, the step of making the holes in one of the leaves of each end pair and the corresponding holes in one of said door and frame exactly to the size of the connecting means passing through them to insure effective stress transmission, and the step of making the holes in one of the middle leaves larger than the connecting means thereby permitting adjustment of small dimensional inaccuracies.
